UNITED STATES PATENT OFFICE.

FRED W. RIDLON, OF SPRINGFIELD, MASSACHUSETTS.

BOILER-FURNACE GRATE.

No. 851,318.

Specification of Letters Patent.

Patented April 23, 1907.

Application filed August 25, 1905. Serial No. 275,792.

To all whom it may concern:

Be it known that I, FRED W. RIDLON, a citizen of the United States of America, and a resident of Springfield, in the county of 5 Hampden and State of Massachusetts, have invented certain new and useful Improvements in Boiler-Furnace Grates, of which the following is a full, clear, and exact description.

This invention relates to grates for furnaces or steam boiler fire-boxes, and more especially to that class known as "rocking bar grates," in which a series of journaled grate bars, each provided with separated 15 and parallel grates or teeth is arranged and supported in suitable bearing frames.

An object of this invention is to provide new and simplified means whereby the grate-bars may be quickly removed, on becoming 20 warped or otherwise defective, and as quickly replaced by new ones.

Other objects equally important are the interchangeability of all parts comprised in the grates, such as grate-bars and grate 25 bar supporting frames, and grate bar rocking means, and the adaptability for assembling all of said parts by interlocking portions without the use of the fastening bolts and screws commonly required in installing 30 rocking bar grates.

The labor and difficulties of installing rocking bar grates comprising screw or bolt fastenings, and the increased difficulties attending the dismounting of the same, owing 35 to the destructive action of heat on screw threaded fastenings, are well known, and the advantages to be derived from the substitution of interlocking jointed connections for screw threaded fastenings will be mani- 40 fest.

To the above ends my invention consists in the novel features of construction fully set forth herein in connection with the drawings, and set forth in the claims.

In the drawings,—Figure 1 is a plan view of 45 a rocking bar grate embodying my invention, and represents a complete assemblage of the various component parts thereof, with the exception of two of the journaled bearing 50 caps, which are understood as removed for clearer illustration of the underlying parts. Fig. 2 is a side elevation of an assembled rocking bar grate, with some parts shown in section, as taken on a line 2—2, Fig. 1. Fig. 3 55 is a perspective view of portions of a rocking bar grate comprised in my invention, said

portions being shown in separated relations to each other. Fig. 4 is a section taken on line 4—4, Fig. 1, of a grate-bar journal-bearing, and Fig. 5 is a side elevation of the same bearing. Figs. 6 and 7 are plan views in representation of some of the variations in arrangement of the grate-teeth. Figs. 8 and 9 are cross sectional views of grate teeth, as taken on a line x—x, Fig. 7, showing variations of forms of the teeth.

Similar characters of reference indicate corresponding parts in all of the views.

In Fig. 1 of the drawings, the rocking bar grates are shown as mounted in two sections 7c in a rectangular shaped frame consisting of the two end bars A, A, which are provided at each end with the legs A' and the locking ribs a, a, and of two side bars B, B, having downwardly extending forked portions b, b, 75 at their ends which interlock with and between the pairs of ribs a, a, of the end frames, thus constituting a quickly assembled and rigid frame support.

A central bar B' having forked end portions 30 b' b' interlocks with intermediately provided locking ribs a' a' in the end frames A A.

The side bars B, B, have provided thereon, at points equi-distant from each other, the circular holes C which form the bearings for 85 the outer end journals or gudgeons c of the grate-bars D, the inner end gudgeons e of which are supported in upwardly open half-round bearings f formed within the upper edge portion on the central bar B'. The two 90 aligned grate bars D of a pair are of such a length that when their ends e are seated in the bearing holes C of the opposite side bars B, B, their inner ends e are both adjacently supported in one bearing f, as clearly shown 95 in Fig. 1. Referring to said Fig. 1 and also to Figs. 3, 4, and 5, F represents the bearing caps or saddles which cover the grate bar inner end journals of a pair, and protect the same from the pressure of the ashes or coal 100 supported on the grate. These caps F are maintained in place over the bearings f by the downwardly projecting separated legs f' thereof, which, as shown in Figs. 4 and 5, closely engage either side of the central bar 105 B', but having no fastening connection with said bar B', they may be quickly placed in their positions of engagement or removed therefrom.

The grate bars D, as best shown in Fig. 3, 110 have provided on either side thereof the equally spaced vertical grooves d and have

also provided on either side thereof the longitudinally extending grooves *h*; these grooves *h* intersect the vertical grooves *d*.

The removable and interchangeable 5 "teeth" *G* as they will be called (shown in perspective in Fig. 3) are each provided with downwardly extending fork-like projections *i i*; and the inwardly facing walls of the opening *j*, formed between the said projections *i i* 10 and which opening extends nearly to the upper edge of each tooth, are formed adjacent the upper portion of the opening with half round grooves *k*. The width of the teeth openings *j* is about equal to the cross sectional thickness of the grate bars *D* at the vertical grooves *d*, thereby ensuring a close supporting engagement of the teeth *G*, with the grate-bars *D*.

An efficient locking device for securing the 20 teeth in their proper positions to the grate bars *D* is provided by the rod *K*, shown in Fig. 3, and in its operative position in the sectional portion of Fig. 2, it being understood that when the fork like teeth are engaged about the grate bars, with the grooves *k* matching with the grooves *h*, the rod is slid into such matching grooves and constitutes a key for interlocking the teeth and bar.

Each grate bar *D* of both sections of a 30 grate, such as shown in Figs. 1 and 2, is provided with downwardly extending rocking arms *M* (excepting the end grate bars *D'* which are held stationary). The lower end portions of these arms *M* have formed there- 35 on the studs *m* which are engaged by the horizontal double connecting bars *N*. The rocking-arm studs *m* at the ends of the double connecting bars *N* are passed through holes *n*, formed in said connecting bars, and 40 pinned or otherwise secured thereto, the rocking arm studs of the intermediate grate bars being engaged with the double connecting bars *N* by entering the notches *n'* formed in the said bars *N*.

45 The grate bars *D* of each section of a grate, mounted and connected together as above described, are provided with means for simultaneously rocking them in the usual manner, consisting in the hinged depending link 50 *O*, attached to one of the end bars *A* of the grate frame, see Figs. 1, 2 and 3, the connecting rod or bar *o* extending from the said link *O* to a point of connection preferably about centrally of the double grate-connect- 55 ing bars *N*.

A square socket *p* formed in the link *O* is adapted to receive the squared end of a shaker rod *P*, shown in perspective in Fig. 3. The operation of the rocking of the grate bars 60 *D* by means of this shaker rod is accomplished by vertically raising and depressing the free end of said rod, and the degree of motion imparted to the grate-bars is limited by the hinged and depending plate or block *Q* hav- 65 ing the stop lugs *q q* formed thereon which

contact with the extended end of the link pivot *o*. When it is desired to "dump" the grate, that is to rock the grate bars in excess of the limited motion before described, the stop plate *Q* is swung upward out of position 70 for engagement with the link pivot extension *o* and is held in such raised position by the hook *R*, which is hooked into the eye shaped stop plate handle *r*.

The location and arrangement of the individual teeth *G* of a sectional rocking bar grate, as shown in Figs. 1 and 2 of the drawings, may be varied to suit different draft requirements therethrough, or for differing sizes of coal or other fuel. 75 80

In Fig. 6 the teeth *G* are shown all placed on the grate bars in the same way instead of being "staggered" or alternately oppositely arranged, as shown in Fig. 1.

In Fig. 7 the teeth *G* are arranged as in 85 Fig. 6, but alternate teeth on each grate bar *D* are shown as removed; in this manner a greater draft opening upwardly through the grate is provided.

Figs. 8 and 9 illustrate arrangements for 90 still further variations in the degree of air space between individual teeth as provided by the before described teeth *G*, and by teeth *G'* as shown in Fig. 9. The teeth *G* are to be provided where the minimum amount of air 95 or draft space is desired, the diminished air space being assured by forming such teeth *G'* with a broader or thickened top or surface portion.

By lifting a cap or saddle *F* from its position of engagement with the middle grate frame bar *B'* and with the adjoining end portions of two aligned grate bars *D*, *D*, each of these bars may be removed (and with it all its teeth) by lifting the inner end of the bar a 100 distance a little more than equal to its diameter, and endwise drawing the bar to disengage its outer journal *c* from its side frame socket *C* therefor.

Having thus described my invention, what 110 I claim and desire to secure by Letters Patent is:—

1. In combination, a grate frame, a series of toothed grate bars journaled in said frame and having depending arms, *M*, a bar *N* engaging the several arms, a rod connecting the said bar *N*, a link hung to a fixed support therefor, as the grate-frame, a block pivoted to and depending from the grate frame alongside said link, having separated lugs extending across the plane of swinging movement of said link, and adapted to swing at right angles to the plane of movement of the link, and means for temporarily confining said block in a position entirely free from engagement 115 with said link. 120 125

2. In combination, a grate frame, a series of toothed grate bars journaled in said frame and having the depending arms *M*, the bar *N* in engagement with the several arms, the rod 130

o connected to said bar N, the link O pivotally hung to the grate-frame, and with which said rod is also connected, the block Q, pivotally hung to the grate frame and depending normally in a position closely alongside said link, said block adapted to swing angularly to the plane of movement of the link and having the separated stops q, q, the eye shaped handle r, and the catch hook R on the grate frame for engaging the said handle r.

3. The combination with a grate frame comprising opposite side bars having horizontally aligned journal sockets, and an intermediate frame bar having upwardly opening journal sockets f of two series of grate-bars having end journals, the oppositely arranged, outer, journals of both series being engaged in the side bar sockets and the adjacent inner ends of the grate-bars being supported in the upwardly open sockets f of the intermediate frame-bar, and the caps or saddles F having the depending fork members mounted on and sidewise engaging the intermediate frame bar, and covering the adjoined journal ends of the grate-bars.

4. The combination with a frame, of a plurality of grate bars, each mounted for rocking movements in said frame, and having means for rocking them, and each grate bar provided with removable teeth, the bar constructed with vertical parallel side grooves, and an intersecting longitudinal groove h, and the teeth comprising heads or top portions and downwardly extending fork like projections, a fork member of each having a groove or niche k to match with the grate bar groove, and the locking rod K, engaging in the longitudinal grate-bar groove, and in the grooves k of the depending forks of the teeth which are removably engaged above and about the grate bar.

5. The combination with a frame, of a plurality of grate bars, each mounted for rocking movements in said frame, and having means for rocking them, and each grate bar provided with removable teeth, the bar constructed with vertical parallel side grooves, and an intersecting longitudinal groove h, and the teeth comprising heads or top portions and downwardly extending fork like projections, a fork member of each having a groove or niche k to match with the grate bar groove, and the locking rod K, engaging in the longitudinal grate-bar groove, and in the grooves k of the depending forks of the teeth which are removably engaged above

and about the grate bar, and each grate bar having a depending arm M and end journals.

6. The combination with a frame, of a plurality of grate bars, each mounted for 60 rocking movements in said frame, and having means for rocking them, and each grate bar provided with removable teeth, the bar constructed with vertical parallel side grooves, and an intersecting longitudinal 65 groove h, and the teeth comprising heads or top portions transversely extending, and projecting farther at one side of the bar than at the other, and downwardly extending fork like projections, a fork member of each having a groove or niche k to match with the grate bar groove, and the locking rod K, engaging in the longitudinal grate bar groove, and in the grooves k of the depending forks of the teeth which are removably engaged 70 above and about the grate bar.

7. In a fire box rocking grate, a frame comprising opposite end bars having vertical ribs at their ends, and pairs of separated vertical ribs at their intermediate portions, opposite side bars B and an intermediate bar B' all having downwardly opening recesses at their end portions, which so formed portions are detachably engaged with the rib provided portions of the end frame bars, said 85 side bars having a series of journal holes C, and said intermediate bar having within its upper edge a series of upwardly open journal sockets f, two series of grate bars having end journals, engaged in said journal holes 9c and sockets with their inner journal ends adjoined, constructed with the longitudinal grooves h, and the vertical grooves d d and having each a depending arm M, a series of grate teeth for the respective bars, each 95 comprising downwardly extending fork like projections, a fork member of each having a transverse groove k to match with said grate bar groove h, the locking rods K, the bars N engaging the several arms M of a grate bar 100 series, a connecting rod secured to each bar N, and a link pivotally connected to each connecting rod and pivotally hung to the grate frame, and adapted to receive engagement therewith of means for oscillating such 105 link.
